UNITED STATES PATENT OFFICE

2,485,922

CHILD'S NOVEL PICTURE HOT PLATE

Elizabeth Rubin, New York, N. Y.

Application September 27, 1947, Serial No. 776,489

3 Claims. (Cl. 65—61)

1

This invention relates to new and useful improvements in child-coaxing food-serving dishes.

By a dish is meant any bowl, saucer, plate or other food container for children.

An important object of the invention is to provide a new and useful combination or assembly including a food dish, and a changeable means to intrigue the interest of the child and stimulate eating of the food. The bottom of the dish is transparent, and the changeable means, operable from the exterior of the combination or assembly by a manipulation performed either with or beyond the sight of the child, functions in such manner that from time to time different pictorial representations, nursery rhymes or the like, those familiar to the child or otherwise, may be selectively interchangeably displayed below the dish for inspection through its transparent bottom. Hereinafter, any of such kinds of display, pictorial or in print, is meant when a picture is referred to.

A further feature of the invention is the provision, in addition to the features above mentioned, of a food-dish-underlying structure or base which provides a chamber for the storage of hot water for keeping the food in the dish from getting cold.

Such base may be a one-part structure, providing merely the hot water chamber, or a space for affording a field of operation for the display means, or providing both said chamber and said space.

A further feature of the invention involves the provision of means whereby with a plurality of separable structures present and with these adapted to rest one on top of another, said structures are so shaped that they may be thus arranged so as dependably to be assembled, merely by gravity and/or interengaging formation.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 shows one now favored embodiment of the invention, in axial section.

Fig. 2 is a top plan view thereof, with the food dish removed.

Fig. 3 is an enlarged axial section, taken on the line 3—3 of Fig. 2, which line is at right angles to the cutting plane on the basis of which the showing of Fig. 1 is made.

2

Fig. 4 is a horizontal section, taken on the line 4—4 of Fig. 3.

Fig. 5 is a perspective view of the bottom structure, looking down on the top of the same.

5 Fig. 6 is a fragmentary detail view on a still larger scale, this view being a section taken on the line 6—6 of Fig. 5.

Fig. 7 is a perspective view of a structure intermediate the food dish and said bottom structure, 10 with the same inverted to show certain formations on the bottom thereof.

Fig. 8 is a fragmentary perspective view, showing a length of a web-type picture-carrying element forming part of the display means.

15 The child's picture hot plate, according to the present invention, includes a food dish 15 made of glass or some other suitable transparent material. Below the food dish is a bowl-shaped structure 16, which may be made of thin metal, some 20 non-transparent plastic, or the like. Below the structure 16 is a base structure 17, which may be made of glass or the like; and which provides a chamber 18 for holding hot water, such chamber being able to be filled with hot water and emptied 25 of the same by way of a spout 19 closable by a stopper 20.

The structure 17, which may aptly be called the chambered base, has a downwardly depressed top wall 21 shaped along the inner side of its upper 30 marginal portion for engaging the bottom side margin of the structure 16 to insure positioning of the latter solidly on the chambered base 17 while at the same time providing a space or compartment 22 for affording a field of operation for 35 the display means.

The structure 16, which may aptly be called the intermediate bowl, has downwardly projected from its bottom two pairs of ears 23. Said ears have apertures 24; these apertures on the ears of 40 each of said pairs being aligned, and the aligning of the apertures of one pair being parallel with that of the apertures of the other pair. Parallel with such alignments are a pair of slots 25 through the bottom of the intermediate bowl 16.

A web 26, of paper, acetate or other suitable flexible material, is suitably attached at its opposite ends to each of a pair of rod-like reels 27 each journaled in the apertures 24 of a pair of 50 the ears 23. Beyond an end length of the web 26 wound on one of the reels 27, the web is passed upwardly through one of the slots 25 and then extended across the upper surface of the bottom of the intermediate bowl 16, thence is extended 55 down through the other slot 25, and thereafter

continues as another end length of the web wound on the other reel 27.

Thus, by rotation of one reel or the other, a predetermined web portion, such as that shown at 28a in Fig. 2, may be displayed in the intermediate bowl 16, between the slots 25, for inspection through the transparent bottom of the food dish 15. The side of the web uppermost during any such display carries a plurality of different pictures, as indicated in Fig. 8; the three pictures there shown being marked 28, 29 and 30.

The reels 27 are extended beyond the outer limits of the intermediate bowl 16 and the chambered base 17, and said reels at their outer ends carry turn-knobs 31. If desired, the pictures may also be made visible along the walls or sides of the plates.

In order to keep all parts of the display means protected against contact by the hot water in the chambered base 17, the latter is provided with a pair of open-topped slots 32 (Figs. 5 and 6), formed in solid masses 33 located at a side of the top marginal portion of said base. These slots are for receiving the reels 27 when the intermediate bowl is placed on the chambered base 17.

Accordingly as one knob 31 or the other is turned in the proper direction, a desired one of the pictures on web 26 may be arranged for inspection as above, as a promised reward to the child when all the food in the dish 15 is eaten.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A picture exhibiting device for use with a child's hot dish including a heating base element and a transparent feeding dish comprising, a member removably supported on the heating base element provided with a horizontal wall spaced from the heated base element, parallel reels rotatably supported beneath the horizontal wall of said member and above said heating base element, spaced slots in said horizontal wall parallel to and intermediate said reels, a display film carried by said reels and passing therebetween

through said slots to display a portion thereof above said horizontal wall, and a portion of said member above said horizontal wall shaped to receive and support a transparent feeding dish at a spaced distance above said wall.

5 2. A picture exhibiting device for use with a child's hot dish including a heating base element and a transparent feeding dish comprising, a member removably supported on the heating base element and provided with a horizontal wall spaced from said element, spaced pairs of ears depending from the bottom of said horizontal wall, parallel reels rotatably supported one between each pair of said ears, spaced elongated slots in said horizontal wall parallel to and intermediate said reels and said ears, a display film carried by said reels, said film being threaded through said slots intermediate said reels to dispose a portion thereof above said horizontal wall between said slots, and that portion of said member above said wall being shaped to support a transparent feeding dish at a spaced distance above said wall.

10 3. A structure as defined in claim 2 wherein, 25 said reels are supported upon parallel rods rotatably mounted in said pairs of ears, and said rods extending through the side of the structure to permit free manual rotation of said reels.

ELIZABETH RUBIN.
